DENTAL STAND UNIT

John A. Maurer, Canton, and David A. Walquist, Wooster, Ohio, assignors to The Weber Dental Manufacturing Company, Canton, Ohio, a corporation of Ohio

Filed Dec. 30, 1965, Ser. No. 373

Term of patent 14 years

(Cl. D24—1)

Fig. 1

Fig. 3

FIG. 1 is a perspective view of the dental stand unit showing the relationship thereof to a dental chair and light which are illustrated in broken lines, and showing our new design with the stand in lowered position and the bowl assembly in retracted position;

FIG. 2 is a view similar to FIG. 1 but with the stand in a raised position and the bowl assembly in an extended position;

FIG. 3 is a view similar to FIG. 1 showing a modified form of the dental stand unit;

FIG. 4 is a fragmentary view similar to FIG. 1 but with the bowl assembly in extended position and the instrument tray extended over the bowl; and

FIG. 5 is a view similar to FIG. 4 but with the instrument tray in retracted position and the bowl assembly and pedestal rotated relative to the remainder of the dental stand unit.

The dominant features of our design reside in the portions shown in full lines.

We claim:

The ornamental design for a dental stand unit, substantially as shown and described.
